S. K. WOOD

CAR IDENTIFYING MEANS

Filed Jan. 21, 1924

Witness: *R. Hamilton* Inventor: *S. K. Wood*

By *Proper Guard* Atty.

UNITED STATES PATENT OFFICE.

STRAUD K. WOOD, OF HUTCHINSON, KANSAS.

CAR-IDENTIFYING MEANS.

Application filed January 21, 1924. Serial No. 687,468.

To all whom it may concern:

Be it known that I, STRAUD K. WOOD, a citizen of the United States, and a resident of Hutchinson, Reno County, State of Kansas, have invented a certain new and useful Improvement in Car-Identifying Means, of which the following is a complete specification.

This invention relates to motor car identifying appliances of that character in which a card is affixed to and displayed on each car and contains the signature and address of the owner, the engine number, the make, model and style of car, the State where issued, etc., there being a duplicate card in the possession of the proper State authorities, and preferably an additional copy to be carried by the driver of the car, for display on demand of a policeman or other State or municipal official, though the said copy is not essential where the original contains the signature of the driver, as in such case the officer can require the driver to write his name as a basis for comparison with the signature on the card displayed on the car.

The object of the invention is to produce a holder of such character that it efficiently protects and utilizes a car-identifying card as a seal so that the card cannot be removed without mutilation, or without injury to the holder, as mutilation of such cards, in many States, is the cause for arrest and investigation. A further object is to produce a holder of the type mentioned, which is of simple, strong, durable and attractive appearance.

With these objects in view the invention consists in certain novel and useful features of construction and organization of parts as hereinafter described and claimed; and in order that it may be readily understood, reference is to be had to the accompanying drawing, in which:—

Figure 1 is a front view of a device embodying the invention, as applied to the windshield of a motor car.

Figure 2 is a rear view of the device.

Figure 3 is a section on the line III—III of Figure 1.

Figure 4 is a vertical section on the line IV—IV of Figure 1.

Figure 5 is an inner face view of a fragment of the rear member of the device.

Figure 6 is an enlarged vertical section on the line VI—VI of Figure 1. 55

Figure 7 is a detail edge view showing the interlocking relation between the front transparent plate and the identification card.

In the said drawing the holder is shown as composed of two sheet steel or equivalent members of rectangular form, secured together and sealed in such relation by an identification card held between the members and readable but not accessible through a window in the front member. 60 65

The back member 1 is pressed out to provide a rectangular recess 2, and is turned or flanged back at its upper end at 3 to provide a downwardly-opening groove or channel. The portion of the member providing the back of the recess, is formed with an opening or window 4, and the member is provided near its lower corners with bolt holes 5 and near its upper margin with a hole 6. Above the window and within the recess, is a pair 75 of resilient hooks 7, formed at opposite ends of a plate 8 secured to the back wall, and provided at its lower margin with a flange 9 between and slightly below the horizontal plane of the hooks. The flange 9 acts as a 80 stop for a transparent plate fitting snugly in the recess below the said flange. The transparent plate is preferably composed of two similar glass sections 10 united to an interposed sheet 11 of isinglass, the latter being 85 transparent and constituting a reinforcement which will hold the glass sections in place even if criss-crossed with a multiplicity of fractures. The plate described is a stock product and hence available, but any 90 transparent plate such as wire-glass, may be used as a substitute.

The front member 12 corresponds in size and form to member 1, but is flanged at its side margins at 13 to provide grooves for 95 the reception of the side edges of the back member, and with an upturned flange 14 at its lower end, to produce a groove for the reception of the lower end of the back member, the upper end of the front member 100 being adapted to enter the groove 3 of the back member. To secure the members together as explained, they are arranged end to end and relatively slid longitudinally to cause the side edges of the back member to 105 engage the side grooves of the front mem-

ber, and when so related they are finally interlocked at all four edges and cannot be separated except by reversing the sliding movement.

- 5 The front member is formed with a recess 15 like recess 2, the plate being pressed outwardly or oppositely so that the two recesses, when the members are interlocked together as explained, form a single compartment. The front member is provided with a window opening 16, with bolt holes 17 to register with holes 5, and with a hole 18 to register with hole 6. A transparent plate 19 of the character described, fits snugly in the recess 15, and a flexible identification card 20 is fitted over its inner face and interlocked with the plate 19 by being bent over the upper and lower ends of the latter as at 21, so that the card cannot slip or buckle 20 between said plate and the corresponding plate of the back member, the plate of the latter forming a smooth backing for the card, as clearly shown.

On assembling the members in interlocked relation as explained, the transparent plates, with the card secured to the front one, are first placed in their respective recesses, and the card during the sliding movement, represses the hooks 6 until a pair of perforations 22 in the former register with the lower ends of the hooks. As this occurs the sliding movement is completed and the hooks enter the said perforations 22 so that the card by engagement with the hooks, 30 serves to seal the members together and make it impossible for them to again separate by reverse sliding movement, without tearing the card from said perforations upward. Nor can the window plates be broken 40 and removed piecemeal to effect the removal of the card without injury to the latter. If the plate 19 is cut out at the margins of opening 16, the card cannot be removed intact, as there would still remain a frame of 45 glass clamping the card at its margins against the plate of the other or back member. It will be apparent, therefore, that it would be impracticable for anyone to readily remove a card for the purpose of replacing it with a fraudulent one, and even if this was done, it would be instantly discovered when an attempt was made to secure a new license, as with this system it is contemplated that the State authorities shall 50 retain a duplicate of the required card and compare same with the original or a replacement thereof, before issuing a new license or permit.

The holder is adapted to be secured upon the wind shield, instrument board or other suitable place on a car. If upon the wind shield, securing bolts 23, mounted in the wind shield frame, are fitted through the registering holes 5 and 7, and wing-nuts 24 or the like, are employed to clamp the two

members together and to the said frame. If the holder is secured to the instrument board or other place, bolts will be engaged with the said holes and with the additional holes 6 and 18 in the rear and front members. 70

If the law requires that the card contain printed matter on the back as well as on the front, the holder will preferably be secured adjacent the wind shield, so that the card may be in convenient position for inspection at both sides. 75

I claim:

1. In a device of the character described, a casing comprising two slidably-related members, and having a window opening, a transparent plate covering the opening, a certificate within the casing and interlocked with the transparent plate, and one or more prongs within the casing and adapted to mutilate the certificate in the event the said members are slidably operated to give access to the interior of the casing. 80

2. In a device of the character described, a casing comprising two slidably-related members, and having a window opening, a transparent plate covering the opening, a certificate within the casing and interlocked with the transparent plate, and one or more spring prongs adapted to engage the certificate and without injury thereto, yield to movement thereof incidental to the sliding of the members together, and to resist movement of the certificate to mutilate the same, when the members are slid in the reverse direction for access to the interior of the casing. 90

3. In a device of the character described, a frame comprising two members slidably interlocked together at opposite edges, and provided with a window opening, one or more resilient prongs within the frame and fixed thereto as regards one of its said members but capable of reposition toward the same, a transparent plate within the casing between said prongs and the said window opening and closing the latter to prevent access to the interior of the casing, and a certificate within the casing between the said plate and prongs for mutilation by the latter in the event the members are slid to effect separating or disengaging movement. 100

4. In a device of the character described, a frame comprising two members slidably interlocked together at opposite edges, and provided with a window opening, one or more resilient prongs within the frame and fixed thereto as regards one of its said members but capable of reposition toward the same, a transparent plate within the casing between said prongs and the said window opening and closing the latter to prevent access to the interior of the casing, a certificate within the casing between the said plate and prongs for mutilation by the latter in the event the members are slid to effect 110

- separating or disengaging movement, means for interlocking the members together at their ends against spreading apart movement and for arresting their slideable movement in one direction when they are fully slid together, and means for securing them against reverse sliding movement.
5. In a device of the character described, a casing comprising a pair of members slidably interlocked together at opposite edges, and provided with a window, one or more resilient prongs within the casing and repressible toward and carried by one of the members thereof, a transparent plate within 10 the casing and closing the said window, and a certificate interposed between the said prongs and plate, and folded around the ends of the latter; the prongs yielding to such sliding movement of the members as 15 shall bring them together, to avoid injury to the certificate, and resisting opposite movement of the members, to effect mutilation of the certificate.
6. In a device of the character described, a casing comprising a pair of members slidably interlocked together at opposite edges and formed within their margins with recesses at their inner or adjacent sides, and provided with a window opening, one or 20 more resilient prongs secured to and within the recess of one of said members and repressible therein but pointed toward the other member, a transparent plate fitting in 25 the recess of the other member and closing the said window, and a certificate interposed between the prongs and plate and fitting flatly against and folded around the ends of the latter, and provided one or more perforations receiving the point or points of the prongs when the casing is in closed condition.
7. In a device of the character described, a casing comprising a pair of members slidably interlocked together at opposite edges and formed within their margins with recesses at their inner or adjacent sides, and provided with a window opening, one or 30 more resilient prongs secured to and within the recess of one of said members and repressible therein but pointed toward the other member, a transparent plate fitting in the recess of the other member and closing the said window, a certificate interposed between the prongs and plate and fitting flatly against and folded around the ends of the latter, and provided with one or more perforations receiving the point or points of the prongs when the casing is in closed condition, means interlocking the end edges of the members against spreading-apart movement when fully closed together, and fastening means extending through the members.
- 35 40 45 50 55 60
- In witness whereof I hereunto affix my signature.

STRAUD K. WOOD.
